CLAIM

The ornamental design for an uninterrupted power supply
for an electronic apparatus, as shown and described.

DESCRIPTION

FIG. 1 is a front elevational view of an uninterrupted power
supply for an electronic apparatus, showing our new design;

FIG. 2 is a rear elevational view thereof;

FIG. 3 is a top plan view thereof;

FIG. 4 is a bottom plan view thereof;

FIG. 5 is a right side elevational view thereof the left side
being symmetrical to the right;

FIG. 6 is a cross sectional view thereof, showing end
surfaces taken along line 6—6 of FIG. 1 with the internal
system omitted;

FIG. 7 is a front, top and right side perspective view thereof;
FIG. 8 is a front, top and right side perspective detail view
showing the display panel cover opened and the display
energized;

FIG. 9 is a top plan detail view of a second embodiment
showing a front corner of our new design with the trans-
parent display cover being tinted. All other aspects of the
second embodiment are the same as the first; and,

FIG. 10 is a top plan detail view of a first embodiment
showing the front corner with the light transmitting portions
of the display hatched in contrast with the rest of the panel.
